(57) CLAIM

I claim the ornamental design for a planter, as shown and described.

DESCRIPTION

FIG. 1 is an upper perspective view showing my new design for a planter;

FIG. 2 is a lower perspective view showing the design of FIG. 1;

FIG. 3 is a side view showing the design of FIG. 1;

FIG. 4 is a top view showing the design of FIG. 1; and,

FIG. 5 is a bottom view showing the design of FIG. 1.

In FIGS. 1-5, the broken lines are for purposes of illustration only and do not form a part of the claimed design.

The broken lines shown illustrate portions of the planter that form no part of the claimed design.
